US0D1089170S

(12) **United States Design Patent** (10) **Patent No.:** **US D1,089,170 S**
(45) **Date of Patent:** **** Aug. 19, 2025**

(54) **ELECTRONIC DEVICE HOLDER**

(71) Applicant: **DONGGUAN PAIFAN ELECTRONIC TECHNOLOGY CO., LTD.**, Dongguan (CN)

(72) Inventor: **Xiaobin Wei**, Shenzhen (CN)

(73) Assignee: **DONGGUAN PAIFAN ELECTRONIC TECHNOLOGY CO., LTD.**, Dongguan (CN)

(**) Term: **15 Years**

(21) Appl. No.: **29/889,474**

(22) Filed: **Apr. 13, 2023**

(51) LOC (15) Cl. **14-03**

(52) U.S. Cl.

USPC **D14/253**; D12/415

(57) **CLAIM**

The ornamental design for an electronic device holder as shown and described.

DESCRIPTION

FIG. 1 is a perspective view of an electronic device holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the electronic device holder of FIG. 1, shown in an alternate position;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the drawings depict portions of the electronic device holder that form no part of the claimed design.

1 Claim, 16 Drawing Sheets
